UNITED STATES PATENT OFFICE.

JAMES WILEY SMALL, OF ROCHESTER, NEW YORK.

MACHINE FOR VENDING AND REGISTERING TICKETS.

1,060,291.

Specification of Letters Patent.

Patented Apr. 29, 1913.

Application filed November 10, 1911. Serial No. 659,598.

To all whom it may concern:

Be it known that I, JAMES WILEY SMALL, a citizen of the United States, residing at Rochester, in the county of Monroe and 5 State of New York, have invented certain new and useful Improvements in Machines for Vending and Registering Tickets, of which the following is a specification.

The subject of the present invention is a 10 machine, placed under the control of the ticket seller, which has a magazine appropriate to the form of the tickets, and which at each operation will deliver a single ticket and register it so that the total number of 15 tickets delivered by the machine will be shown at a glance.

The present application is one of a series of applications which were filed on the dates and bear the serial numbers following, to- 20 wit: April 29, 1911, Serial No. 624,031, upon which Patent Number 1,022,159 was issued April 2, 1912; Oct. 20, 1911, Serial No. 655,672; March 16, 1912, Serial No. 684,187, and April 29, 1912, Serial No. 25 693,908. These applications relate to machines for vending postage stamps, tickets and similar articles, and to machines for affixing stamps, labels and similar articles to letters, parcels and the like. All of these 30 machines include mechanism for feeding forward, step by step, a strip or ribbon comprising a number of such stamps, tickets, or the like, and means for severing the tickets, one at a time, from the strip, 35 but I desire to have it understood that none of the claims in any of said applications is to be considered as having been abandoned or dedicated to the public by reason of the fact that its subject matter is shown and de- 40 scribed, but not claimed, in any other of said applications.

The object of the invention which forms the subject of the present application, stated generally, is to provide a machine which 45 will accurately vend tickets for different uses, one at a time, especially when the tickets are printed consecutively on a continuous strip of paper or other suitable material of indefinite length.

More particularly stated, the objects of 50 the invention are to advance the ticket strip a distance exactly equal to the length of a single ticket at each operation of the machine; to provide feed mechanism having feed dogs which are manually retracted by movement derived from the cutting mecha-

nism during its operation of severing the ticket and automatically advanced by the recoil of a spring which is manually put under tension by the operation of the cutting mechanism; to lock the vending mechanism and close the delivery opening of the casings by means which is concealed and protected as against surreptitious access, and, generally to improve the efficiency of 65 the machine.

To these ends the invention consists in the features of novelty that are hereinafter described with reference to the accompanying drawings, which are made a part of this 70 specification and in which:

Figure 1 is a sectional elevation of a ticket vending and registering machine embodying the invention with one side of the casing removed, all of the movable parts being 75 shown in elevation, while the ticket race is shown in vertical section on line 1—1, Fig. 3 and a fragment of the magazine being shown. Fig. 2 is an elevation of the delivery end of the machine, the operating lever 80 being shown in section. Figs. 3 and 4 are vertical transverse sections on the lines 3—3 and 4—4, Fig. 1, looking in the directions of the arrows, respectively. Fig. 5 is a horizontal section taken practically on the 85 line 5—5, Fig. 1, looking downward. Fig. 6 is a detail showing the mechanism for locking the machine. All of the foregoing figures are drawn on practically full scale. Fig. 7 is a side elevation on a smaller scale 90 of a machine embodying the invention.

For the purpose of this application I have shown the invention as embodied in a machine which is adapted to vend tickets which are printed upon a continuous strip 95 which is afterward done up in the form of a roll, but it will be manifest that some features of the invention are applicable to the vending and registering of tickets of other forms, and I therefore reserve to myself the exclusive right to use the several features of the invention in any machine in which they are capable of use. The machine shown in the drawings has a circular magazine, 10, which contains the roll, 11, of 100 tickets that is supported by a trunnion, 12. For facility in placing the roll of tickets within the magazine, the latter is formed in two parts (practically halves) which are hinged together, as at 13, and one of these 105 parts is provided with a chute, 14, for guiding the free end of the ticket strip to the

delivering and registering mechanism. The individual tickets may or may not be separated by weakened lines but they must be provided with such physical features that 5 will provide shoulders adapted to be engaged by the feed dogs and oppositely presented shoulders which are adapted to engage and actuate the registering mechanism. To this end one or both edges of the ticket 10 strip are provided with a series of notches 15 and 15^a, which preferably occur between adjacent tickets.

From the chute, 14, the tickets pass on to the bottom, 16, or a race, which extends completely 15 through the casing 17, to the delivery end, 18, thereof, which latter is provided with an opening 18^a through which the tickets emerge. This race comprises the bottom (16) and two sides, 19, which are 20 just sufficiently far apart to allow the tickets to pass freely between them, without binding. The bottom (16) of the race is provided in its top side with parallel grooves, 20 and 20^a, which are of sufficient distance apart to 25 register with or lie beneath the notches, 15 and 15^a, respectively in the sides of the ticket strip. The ticket strip is held down upon the bottom of the race, especially where it is engaged by the feed dogs and the registering 30 mechanism, by a plate spring, 21, one end of which, 22, is secured to the receiving end, 23, while the other end, 24, rests upon the ticket strip, by which and an inclined guide, 25, the free end of the ticket strip is 35 guided into the aforesaid opening through the delivery end, 18^a of the casing.

The tickets are fed forward by a pair of spring pressed dogs, 26 and 26^a, the toes of 40 which are adapted to enter the notches of the ticket strip. These feed dogs are in the form of levers which are independently fulcrumed upon a pin, 27, carried by a pendent hanger preferably formed of two parts, 28 and 28^a, the upper ends of which parts are 45 rigidly secured to flanges of an arbor, 29, loosely fulcrumed in the front and back of the casing, spacing sleeves, 30, being loosely mounted upon the arbor between the casing and the hanger for the purpose of permitting 50 the hanger to swing freely and at the same time confine it to proper position. The dogs are held yieldingly in engaging positions by delicate coiled springs, 31 and 31^a, each of which is connected at one end to the 55 projecting heel end of the dog and at the other end to the hanger, and in order to prevent the lower ends of the two parts of the hanger from clamping and binding the dogs, so as to prevent their absolutely free 60 movement they are spaced apart by shoulders on the rivets, 28^b, by which they are connected. The dogs are reciprocated back and forth each time through a distance equal to the length of a single ticket, by the oscillation 65 of the hanger, and this oscillation is

produced by a bell crank lever, 32, one arm, 33, of which has a radially disposed slot, 34, into which projects a pin, 35, carried by the hanger, while the other arm, 40, of said bell crank lever is engaged by an anti-friction 70 roller, 41; carried by one arm of the main or operating lever, 42, which is fulcrumed to the casing at 43, whence it projects outward through the slot, 44, in the delivery end, 18, of the casing and is provided at its outer end with a suitable handle, 45. The main lever, 42, is held in normal position, *i. e.*, with the handle, 45, up, by the heavy coiled spring, 46, and this spring, acting through the main lever, will hold the feed dogs in forward 80 positions, acting through the medium of the bell crank lever, 32, the pin, 35, and the hanger in opposition to the resistance of a lighter coiled spring, 47, which is connected at one end to the hanger and at the other end is anchored to the casing. The depressing of the handle will put the main spring, 46, under tension and will allow the spring, 47, to rock the bell crank lever in the direction of the arrow placed upon it (counter clockwise), and this in turn will oscillate the hanger, thereby retracting the dogs to position for engaging the next succeeding notches, 15 and 15^a. For the purpose of limiting the movement of the parts under 90 the influence of the spring, 47, and thereby stopping the advancing movement of the dogs at the proper point, a stop pin, 32^b, is secured to the casing in the path of the arm, 33, of the bell crank lever. When the pressure upon the handle is released, the main spring will contract and thereby depress the anti-friction roller, 41, and rock the bell crank lever and hangers clockwise in opposition to the resistance of the coiled 100 spring, 47. This again advances the feed dogs and feeds the ticket strip forward a distance equal to the length of one ticket, but the advancing movement of the dogs is always regulated and controlled by the hand lever through the medium of the bell crank lever, 32, and the anti-friction roller, 41, thereby preventing the shocks and jars that would result from the advancing movement of the dogs if they were released instantaneously and thereafter unrestrained. Thus it will be seen, the conditioning of the feed mechanism to operate is produced automatically by the spring, 47, when the hand-lever is depressed, while the operation of actually feeding the ticket strip forward is produced automatically by the spring, 46, acting through the medium of the anti-friction roller, 41. 110

Normally one ticket is always protruding 125 from the delivery end of the casing, as shown in Fig. 7, and the depressing of the handle cuts off this ticket, and, as before stated, conditions the feeding mechanism to feed another ticket forward when the han- 130

dle is released. For cutting off the tickets the main lever is provided with a projection, 48, providing a shoulder which engages a pin, 49, projecting from a cutting blade, 50, fulcrumed at 51, and operating in conjunction with a leger blade, 52, at the delivery end of the casing. The cutting blade, 50, is held normally elevated by a spring, 53, one arm of which engages a pin, 54, carried by the blade, while the other arm is anchored by a screw, 55, an intermediate portion of the spring being coiled around the fulcrum screw, 51, for the purpose of giving the spring the necessary elasticity. A spring washer, 56, is arranged between the head of the fulcrum screw, 51, and the blade for the purpose of holding the latter in proper cutting position relatively to the leger blade.

The sole function of the mechanism thus far described in detail, is to sever and deliver the tickets, one at a time, and has nothing whatever to do with the registering of the delivered tickets excepting that the registering mechanism derives its movement and actuating power from the ticket strip as the latter advances, so that if the supply of tickets becomes exhausted, or for any other reason a ticket is not fed forward by the operation of the mechanism so far described, the registering mechanism will not be operated. On the other hand, if the handle is not depressed to operate the feeding mechanism and one or more tickets are drawn out, the fact will be registered. The registering mechanism has an adding train, 57, suitably supported within the casing but so as to be visible from the outside thereof. This adding train may be of any suitable or known construction and has a link, 58, mounted upon its shaft, 59, so that each time it is oscillated it will advance the unit wheel one point. To the outer end of this link, is pivotally connected the upper end of the thrust rod, 60, the lower end of which is pivoted at 61 near the outer end of a link, 62, the other end of which latter is pivoted to an arm, 63, of a bracket, 64, located within and suitably secured to the casing. To the outer end of the link, 62, preferably beyond the pivot, 61, is pivoted a star wheel, 65, which is located in the vertical plane of the groove, 20, of the ticket race. As shown in the drawing this star wheel has three equidistant arms or teeth, 65^a, 65^b, and 65^c, and the extremity of each of the teeth is provided with a notch to insure its engagement with the shoulders of the ticket strip, which are provided by the notches, 15. This star wheel is supported solely by a link, 62, and is therefore "floating", or in other words capable of moving bodily up and down in an arc struck from the pivotal center of the link, 62. Normally the two adjacent teeth (65^a and 65^b) of the

star wheel rest upon the upper surface of the ticket strip and the star wheel is constantly urged downward by a delicate coiled spring, 66, the lower end of which is anchored at 67 to the bracket, 64, and the upper end of which is connected at 68 to the thrust rod, 60.

All of the parts of both the feeding and registering mechanism are shown in their normal positions before the commencement of the vending operation in all of the several figures of the drawings.

In order to keep the delivery slot 18^a closed so as to prevent the delivery of tickets through it until by a manual operation it is permitted to be again automatically opened in the normal operation of the machine, a lock or detent is automatically moved into engagement with a movable part of the mechanism for closing the opening, 85 after a predetermined operation of the cutting mechanism, and in order to prevent the freeing of the feeding and cutting mechanism from the detent by unauthorized persons. The detent is concealed and protected by a suitable lock, as 71, so as to be inaccessible excepting to authorized persons.

The invention is not limited to means of any particular construction for concealing, protecting and locking the detent, as any means suitable for the purpose may be used.

The detent for locking the mechanism and keeping the opening closed is best shown in Fig. 6. It consists of a slide 72, lying against the inner face of a side of the casing and having through it a longitudinal slot 73 through which passes the non-circular shank of a bolt 74 having an enlarged head, 75, which bears against the inner face of the slide and holds it in place, while permitting it to slide over the bolt transversely thereof, the extent of its movement being limited by the length of the slot and passes loosely through a perforation through the wall of the casing, its projecting end being 110 screw threaded for the reception of a milled thumb nut, 76. By tightening this nut, the slide is locked and prevented from moving endwise, while by loosening it the slide is left free to be moved by a spring 77. The forward end of the slide lies in the vertical plane of the operating lever, 42, and has an inclined surface, 78, which is adapted to engage the rear end of the lever. When the thumb nut, 76, is tightened, the slide is inactive, but when the nut is loosened, the spring, 77, impels the slide forward, causing it to be automatically projected beneath and engage the under side of the rear end of the lever, when the latter reaches its highest 125 position. While in this position the knife blade, 50, is down, having just completed the severing of a ticket, and closes the delivery opening 18^a, until the arm is again moved by the main spring, 46. This, as already 130

stated, is prevented by slide 72, acting as a 5
detent, and the slide can be withdrawn from
its locking engagement with the main lever
only by a manual operation by an authorized
person. Any means for manually operating
the slide may be used. It may have a per- 10
foration 79, adapted to receive a hook or
other implement introduced through a suit-
able opening of the casing but, as before in-
timated, this opening, wherever located or
of whatever character is protected by a
lock, as 71.

What I claim as new and desire to secure
by Letters Patent is:

1. In a machine of the class described the
combination of a ticket magazine, mech- 15
anism for feeding the tickets forward, step
by step, automatically operating mechanism
having a spring for retracting the feeding
mechanism, a main spring superior in 20
strength to the retracting spring for advanc-
ing the feeding mechanism and manually
operable mechanism including the hand de-
vice by which the machine is normally oper- 25
ated for putting the main spring under ten-
sion.

2. In a machine of the class described the
combination with a casing having means for 30
supporting a strip of tickets, or the like, of
mechanism having a reciprocable part for
feeding the strip forward, step by step, a
spring for automatically retracting said re- 35
ciprocable part after each feeding operation
and conditioning it for the next operation,
a main spring superior in strength to the
retracting spring, mechanism interposed be- 40
tween said main spring and reciprocable
part for advancing the latter in opposition
to the force of the retracting spring, and a
hand-lever engaged by the main spring for 45
putting it under tension when manually
operated, which hand-lever is in turn auto-
matically restored to normal position by the
main spring upon the release of the hand-
lever.

3. In a machine of the class described, the
combination of a ticket magazine, and mech- 50
anism for feeding the tickets forward, one
at a time, said feeding mechanism having
a reciprocable dog and means for reciprocating
it, said reciprocating means having a 55
spring for advancing the dog, means having
a hand lever for retracting the dog in
opposition to the resistance of said spring,
and means whereby the advancing move-
ment of the dog is restrained and controlled
by the hand lever.

4. In a machine of the class described, the
combination of a ticket magazine, and mech- 60
anism for feeding the tickets forward, one
at a time, said feeding mechanism having
a reciprocable dog and means for reciprocating
it, said reciprocating means having a 65
spring for moving the dog in one direction,
a hand lever for moving it in the opposite

direction, and a second spring, superior in
strength to the spring aforesaid, for moving
the hand lever.

5. In a machine of the class described, the
combination of a ticket magazine, and mech- 70
anism for feeding the tickets forward, one
at a time, said feeding mechanism having a
reciprocable dog and means for reciprocating
it, said reciprocating means having a 75
depending hanger to which the dog is piv-
oted, a spring acting constantly upon said
lever for moving it in the direction which
retracts the dog, a bell crank lever, one arm
of which engages the hanger and a hand le- 80
ver in contact with which the other arm of
the bell crank lever is held constantly by
the action of the spring aforesaid, whereby
the movement of the parts is placed under
manual control.

6. In a machine of the class described, the
combination of a ticket magazine, and mech- 85
anism for feeding the tickets forward, one
at a time, said feeding mechanism having
an oscillating hanger to which the dog is 90
pivoted, a spring for retracting the dog, a
bell crank lever, one arm of which engages
the hanger, a hand lever engaging the other
arm of said bell crank lever, and a spring
superior in strength to the spring aforesaid 95
for lifting the hand lever and retracting the
dog.

7. In a machine of the class described,
the combination of a ticket magazine, cut- 100
ting mechanism having a blade, a movable
part having a handle, means for transmit-
ting movement from said movable part to
said blade, mechanism for feeding the tick-
ets forward one at a time, said feed mech- 105
anism having a hanger, a dog carried thereby,
a bell crank lever interposed between
said hanger and the movable part aforesaid,
a spring for moving the hanger in the direc-
tion to advance the dog as the movable part 110
aforesaid is moved in the direction to retract
the blade, and a spring for moving said
movable part in the direction to retract the
blade.

8. In a machine of the class described, the
combination of a ticket magazine, a ticket 115
race, mechanism for feeding forward a
strip of tickets, one at a time, said feeding
mechanism having a reciprocable dog,
means for reciprocating it, and a presser
spring for engaging the ticket strip and 120
holding it down upon the race, said presser
spring being in engagement with the ticket
strip throughout the entire range of travel
of the dog.

9. In a machine of the class described, the
combination with means for supporting a 125
plurality of tickets, and mechanism for
feeding the tickets forward and delivering
them one at a time, of an automatically en-
gaging detent for automatically engaging
and locking the feeding mechanism in in- 130

operative condition and manually operable means located within the casing and thereby made inaccessible for rendering the detent inoperative.

10. In a machine of the class described, 5 the combination with means for supporting a strip of tickets, mechanism for feeding the tickets forward, one at a time, and cutting mechanism for severing the ticket strip, of an automatically operating detent for 10 automatically engaging and locking the feeding mechanism in inoperative condition until released manually and manually operable means located within the casing and thereby made inaccessible for rendering the 15 detent inoperative.

11. In a machine of the class described, 20 the combination with a casing having means for supporting a plurality of tickets and an opening through which said tickets are delivered, of means for feeding the tickets forward and delivering them through said delivery opening, one at a time, of means for closing said delivery opening immediately prior to the commencing of each forward 25 operation of the feeding mechanism, automatically operating means for locking said closing means in its position closing the opening, said locking means being retractable only manually, and manually operable means located within the casing and thereby made inaccessible for rendering the automatically operating detent inoperative.

12. In a machine of the class described, 30 the combination with means for supporting 35

a plurality of tickets, and mechanism for feeding them forward and delivering them, one at a time, of a detent automatically operable for engaging and locking the feeding mechanism, said detent being manually operable for retracting it, said detent having a slide adapted to engage a movable part of the means for normally holding the feed mechanism in retracted position and for manually releasing it to permit its automatic 40 engagement with the feeding mechanism and means for preventing surreptitious access to the slide for manually retracting it.

13. In a machine of the class described, 45 the combination with a casing adapted to contain a strip of tickets and having an opening through which the tickets are delivered, cutting mechanism having a blade adapted to close said delivery opening, mechanism for feeding the ticket strips forward, step by step, an automatic detent adapted to engage a movable part of the cutting mechanism for locking it when the delivery opening is closed by the knife, said detent being retractable, an automatically engaging 50 detent for automatically engaging and locking the feeding mechanism in inoperative condition and manually operable means located within the casing and thereby made inaccessible for rendering the detent 55 inoperative.
